CONVERTIBLE TOY

William T. Braman, Newark, N. J.

Application April 8, 1946, Serial No. 660,574

1 Claim. (Cl. 46—201)

1

This invention relates to toys; and the invention has reference, more particularly, to a novel construction of convertible toy adapted to be optionally arranged to simulate different forms of transport conveyances.

The invention has for an object to provide a novel construction of convertible toy adapted, in one arrangement of its parts, to simulate a surface craft or vehicle, such e. g. as a boat or automobile, and, in another arrangement of its parts, to simulate an aeroplane.

The invention has for another object to provide a convertible toy of the kind mentioned comprising a surface conveyance simulating body having movable parts incorporated therewith adapted, when collapsed, to be confined and substantially concealed within the body interior so as to merge with the external contours thereof, whereby the surface conveyance simulating appearance of the body is not substantially altered thereby, but which, when extended, are adapted to form exteriorly projected and properly positioned wing and tail portions, whereby the body is converted to simulate an aeroplane in appearance.

Other objects of this invention, not at this time more particularly enumerated, will be understood from the following detailed description of the same.

Illustrative embodiments of the invention are shown in the accompanying drawings, in which:

Fig. 1 is a side elevational view of a convertible toy according to the invention, the body of which simulates in form that of a boat or water craft, the movable parts being disposed in collapsed positions; Fig. 2 is a horizontal sectional view, taken on line 2—2 in Fig. 1, but drawn on an enlarged scale, and wherein the movable parts are shown by broken lines in collapsed positions, and by full lines in extended positions which convert the toy to its aeroplane simulating appearance; Fig. 3 is a longitudinal sectional view, taken on line 3—3 in Fig. 2; and Fig. 4 is a perspective view of the toy as arranged to simulate an aeroplane appearance.

Fig. 5 is a side elevational view of the convertible toy in a form thereof wherein the body simulates that of an automobile or land vehicle, the movable parts being disposed in collapsed positions; Fig. 6 is a side elevational view, with the movable parts extended to convert the toy to its aeroplane simulating appearance; and Fig. 7 is a horizontal sectional view, taken on lines 7—7 in Fig. 6, the movable parts being shown by broken lines in collapsed positions.

Similar characters of reference are employed

2

in the hereinabove described views, to indicate corresponding parts.

Referring to Figs. 1 to 4 inclusive, the body of the toy, in the form therein shown, is shaped to simulate the appearance of a boat or water craft, and to this end comprises a hull section 10 and a deck section 11 which is superposed upon and suitably secured to said hull section. The top of said hull section 10 is cut away to provide a rearwardly open longitudinal chamber 12 beneath said deck section 11. The opposite side walls 13 of said chamber 12 are pierced to provide lateral elongated openings 14. At the rearward or stern end portions thereof, both the hull section 10 and deck section 11 are cut away at opposite sides to provide inwardly offset lateral receiving seats 15 which intersect the rearward or sternward end of the hull section chamber 12. Extending between said seats 15 is a transverse slot 16 coincident with the plane of the bottom of said hull section chamber 12.

Mounted in said hull section chamber 12, for in and out sliding movement relative to the hull section 10, is a slide member 17. The rearward portion of said slide member 17 is cut away to provide an opening 18, and is shaped to simulate the appearance of an aeroplane tail section 19, which includes a transverse stabilizer simulating section 20. Extending right angularly to the respective sides of said stabilizer section 20 are rudder simulating sections 21, which are outwardly offset from the sides of said slide member. Formed in connection with the hull section 10, inwardly of the transverse slot 16 is an upwardly, centrally positioned stop member or post 22, which extends through the opening 18 of the slide member 17.

Pivottally connected at 23 to the inner end or nose of said slide member 17 are the respective inner ends of a pair of oppositely disposed aeroplane wings simulating members 24. Each said wing member 24 is provided in its inner end portion, and disposed in outwardly offset relation to its pivotal connection with the slide member 17, with a movement guiding slot 25. Each said guide slot 25 cooperates with a stationary guide pin 26; said pins being affixed to the hull section 10 for upward extension through said slots 25. Said wing members 24 are disposed in the planes of the elongated lateral openings 14 with which the side walls 13 of the hull section chamber 12 are provided, whereby to be outwardly projectible through said openings 14.

When the slide member 17 is slid forwardly within the hull section chamber 12, the wing members 24 will be caused to swing inwardly

about the pivotal connection 23 thereof with said slide member 17, such in-swinging movements thereof being properly directed and controlled by the slot and pin connections 25—26. By the time the slide member 17 reaches the limit of its inward sliding movement into the hull section chamber 12, the wing members 24 will be wholly withdrawn into the hull section interior, and disposed therein in longitudinally extending positions, with their forward longitudinal marginal portions lodged within the openings 14, and arranged substantially flush with the external sides of the hull section, thus closing said openings 14. When the slide member 17 reaches the limit of its inward movement into the hull section chamber 12, the tail section 19 and stabilizer simulating section 20 at the rear thereof will be telescoped into said chamber 12, and at the same time the rudder simulating sections 21 will be moved into the receiving seats 15, thus merging the same with the stern end portion of the hull section. It will therefore be obvious that, under such collapsed condition of the movable parts of the toy, the aeroplane simulating features thereof will be entirely withdrawn into and merged with the hull section, so that the conventional appearance of a boat or water craft is attained (see Fig. 1).

To convert the toy from its conventional boat or water craft appearance to an appearance simulating that of an aeroplane, the slide member 17 is longitudinally withdrawn from the stern end of the hull section 10 until stopped by abutment of the forward or inner end margin of its opening 18 against the stop member or post 22. Said outward movement of the slide member 17 projects the tail section 19, together with the stabilizer section 20 and rudder sections 21, to exteriorly extended relation to the stern of the hull section 10. At the same time, the rearward movement of the slide member 17 out-swing the wing members 24, as guided by the slot and pin connections 25—26, through the openings 14 of the hull section 10, and thence to laterally projected transverse extension from the sides of said hull section, all whereby the toy is converted to an aeroplane simulating appearance (see Fig. 4).

In Figs. 5 to 7 inclusive is shown a modification of the invention which provides the convertible toy in a form shaped to simulate the appearance of a land vehicle, such e. g. as an automobile, which, by manipulation of associated movable parts may be converted to simulate the appearance of an aeroplane. To this end, the toy comprises a main body 30 suitably designed to present a streamlined automobile body shape, provided with forward wheels 31. Said body 30 is provided in its lower part with a rearwardly open slideway 32, and laterally open wing housing chambers 33. Longitudinally slidable within said slideway 32 is a slide member 34, the rear portion of which is adapted to provide an aeroplane simulating tail member, which terminates at its rearward end in oppositely extending transverse stabilizer sections 35 and a medial upstanding rudder section 36. Affixed to the underside of rearward end of the slide member 34 is a rear or tail wheel 37. Said slide member 34 is provided with a longitudinal opening or slot 38, through which extends a stationary stop member or post 39 with which the body 30 is provided. Pivots connected at 40 to the inner end of said slide member 34 are the respective inner ends of a pair of oppositely disposed aeroplane wing simulat-

ing members 41. Each said wing member is provided at its inner end portion, and disposed in outwardly offset relation to its pivotal connection with the slide member 34, with a movement guiding slot 42. Each said guide slot 42 cooperates with a stationary guide pin 43; said pins being affixed to the body 30 for upward extension through said guide slots.

When the slide member 34 is slid forwardly into the body 30, the wing members will be caused to swing inwardly, so as to be withdrawn into the wing housing chambers 33 flush with the external sides of the body 30, and at the same time the stabilizer sections 35 will be telescoped into the rear end of said body 30, thus giving the toy the automobile appearance (see Fig. 5). To convert the toy from said automobile appearance to an appearance simulating that of an aeroplane, the slide member 34 is longitudinally withdrawn from the rear end of the body 30 until stopped by the stop member or post 39. Such outward movement of the slide member 34 projects the rear end portion thereof, and the stabilizer and rudder sections connected therewith, into outwardly extended relation to the rear end of the body 30, while at the same time such rearward movement of the slide member 34 outswings the wing members 41 to laterally projected transverse extension from the sides of the body 30, all whereby the toy is converted to an aeroplane simulating appearance (see Figs. 6 and 7). The broken lines in Fig. 7 show the closed position.

I am aware that various changes could be made in the convertible toy structure of this invention without departing from the scope of the invention as defined in the following claim. It is therefore intended that all matter contained in the foregoing description or shown in the accompanying drawings shall be interpreted as illustrative and not in a limiting sense.

I claim:

A convertible toy comprising a body simulating a surface type of transportation conveyance, a longitudinal slide member housed within said body subject to outward extension therefrom, means to limit outward extension of said slide member, the outer end portion of said slide member being shaped to simulate the tail structure of an aeroplane, wing members pivotally connected with the inner end of said slide member, said body having lateral openings in its opposite sides to accommodate said wing members, and cooperative pin and slot connections between said wing members and body adapted to guide swinging movements of the former, said wing members being inswung into the body interior and to longitudinally folded relation to said slide member when the latter is moved into said body interior and outswung to transversely extended projection respectively from opposite sides of said body when said slide member is outwardly withdrawn, whereby, in the latter case, to convert the toy from the appearance of said surface type conveyance to that of an aeroplane.

WILLIAM T. BRAMAN.
